UNITED STATES PATENT OFFICE.

AUSTIN R. DICKINSON, OF SYRACUSE, NEW YORK, ASSIGNOR TO THE SYRACUSE SPECIALTY MANUFACTURING COMPANY, OF SAME PLACE.

DESIGN FOR A CURRYCOMB.

SPECIFICATION forming part of Design No. 24,546, dated August 13, 1895.

Application filed June 19, 1895. Serial No. 553,367. Term of patent 7 years.

To all whom it may concern:

Be it known that I, AUSTIN R. DICKINSON, a citizen of the United States, residing at Syracuse, in the county of Onondaga and State of New York, have invented and produced a new and original Design for a Currycomb, of which the following is a specification, reference being had to the accompanying drawings, showing a part thereof.

Figure 1 shows a top plan or face view of the currycomb; and Fig. 2 shows a side elevation of the same, these views being deemed necessary to fully illustrate my design.

The leading feature of my design consists of an oblong plate A, made up of overlapping sections *a a a*, having a scalloped or serpentine configuration extending across from end to end, as shown in the drawings.

B indicates the shank for the handle secured to the top of the base-plate A.

C is the handle mounted on the shank, and D D are short curved pieces or horns arranged near the front end of the plate.

The construction presents to the eye an attractive and pleasing effect.

What I claim is—

The design for a currycomb, consisting of an oblong plate made up of overlapping sections having a scalloped or serpentine configuration extending from end to end, substantially as herein shown and described.

AUSTIN R. DICKINSON.
